TOY GUN AND COCKING MECHANISM
THEREFOR

Roy Nasello, Brooklyn, N. Y.

Application March 5, 1948, Serial No. 13,192

3 Claims. (Cl. 124—27)

1

My invention relates to toy rifles, and more particularly to a toy rifle of the repeater type whereby the user of the rifle may fire a plurality of bullet-simulating slugs successively without reloading.

With the foregoing in view, an object of the invention is to provide an improved toy repeater rifle.

A further object of the invention is to provide an improved toy repeater rifle of the spring-action type which is simple in construction, attractive in appearance, easy to load and fire, and which is strong and sturdy in use.

A further object is to provide an improved toy repeater rifle which includes a detachable magazine containing a plurality of bullet-simulating slugs together with means for automatically feeding such slugs into the barrel of the rifle after successive firings of the same.

A further object is to provide an improved magazine for a toy repeater rifle.

A further object is to provide an improved toy repeater rifle which includes novel means for cocking the rifle after each shot.

Other objects and advantages reside in the particular structure of the invention, the particular structure of the several parts composing the invention, combination and arrangement of such parts, and will be readily apparent to those skilled in the art upon reference to the attached drawing in connection with the following specification, wherein the invention is shown, described and claimed.

In the drawing:

Figure 1 is an elevational view of a toy repeater rifle constructed in accordance with the present invention;

Figure 2 is a fragmentary longitudinal horizontal section on an enlarged scale and taken substantially on the plane of the line 2—2 of Figure 1;

Figure 3 is a view like Figure 2, but showing the parts in another position;

Figure 4 is a fragmentary longitudinal vertical section through the rear portion of the gun;

Figure 5 is a fragmentary front elevation of the device according to the invention;

Figure 6 is a perspective view showing a detail of the firing pin.

Referring specifically to the drawing, wherein reference characters have been used throughout the several views to designate like parts, 10 designates generally the stock for a gun including a butt 11 and a hand grip 12 which extends forwardly under a barrel 13. As is best

2

seen in Figure 4, the rear end of the barrel is closed by any suitable plug 14. The rear end of the barrel is secured to the stock 10 in any suitable manner, as by the bolt 15 which extends downwardly through the plug 14 and barrel 13. The bolt 15 may also comprise means for anchoring the rear end of a firing pin spring 16, the forward end of which is detachably secured in any suitable manner, as by the transverse pin 17, to a firing pin 18 which is preferably formed with an enlarged head 19. As seen in Figure 1, the forward end of the hand grip 12 is secured to the barrel 13 by a band or hoop 20. A pin 22 extends transversely of the stock 10 in the region of the rear end of the barrel and provides a fulcrum for a double-armed lever, one arm 23 of which extends downwardly and outwardly of the stock to provide a trigger, while the other arm 24 extends forwardly within the stock in a recess 25 formed therein. The forward end of such arm 24 is provided with an upwardly-directed lug 26 comprising a sear. A downward continuation of the recess 25 comprises a slot 27 to permit free action of the trigger-providing lever arm 23. The sear 26 extends upwardly into the barrel 13 through an aperture 28 formed in the lower part thereof and is adapted to engage over the forward end of the enlargement 19 of the firing pin when the latter is moved to a cocked position against the action of the spring 16, whereby to maintain the firing pin cocked. A trigger spring 29 is positioned in a recess 30 formed in the floor of the recess 25 below the sear-providing arm 24. The bottom of the spring recess 30 may be conveniently closed by a set screw 31 to permit access to the spring and/or replacement thereof. As is readily apparent from Figure 4, the spring 29 loads the sear 26 in an upward direction through the aperture 28, whereby the sear automatically engages the front surface of the plunger 19 upon cocking of the latter.

The rear portion of the barrel 13 is formed with a laterally-directed and longitudinally-extending slot 32 therein to permit cocking of the piece by means now to be described. A pair of blocks 33 are secured in any suitable manner, not shown, to one side of the stock in the region of opposite ends of the slot 32. Such blocks 33 have a pair of rods 34 connecting the same to provide a slideway. The slideway-providing rods 34 are parallel to the slot 32 and laterally spaced from the stock 10. A block 35 comprising a slider is slideable on the slide rods 34 to provide a mount for the cocking means for the rifle. A cocking lever 36 has one end pivoted to the slider 35 by

any suitable pivot means 37. The other end of the cocking lever has formed thereon a laterally-directed handle 38 simulating the bolt handle of the rifle. The pivot 37 extends laterally of the slider 35, whereby the cocking lever 36 is mounted for pivotal movement in forward and rearward directions. An upper rear surface of the cocking lever 36 provides a cam surface 39 and an intermediate portion of the rear edge of the cocking lever below such cam surface 39 is cut away to provide a notch 40 which is adapted to engage a laterally outwardly-directed pin 41 fixed to the slider 35, whereby to provide a stop for limiting rearward pivotal movement of the lever 36. A similar pin 42 extends laterally outwardly of the slider 35 to provide a limit stop limiting pivotal movement in a forward direction.

A vertically-directed pivot 43 extends upwardly of the slider 35 and pivotally mounts the inner end of an arm 44 of a cocking pawl 45. A forward arm 46 of the pawl 45 is adapted to be projected from a retracted position outwardly of the barrel 13 to an operative position inwardly of the barrel 13 through the slot 32 for engaging the head 19 of the firing pin to cock the latter upon rearward movement of slider 35. An outer surface 47 of the arm 44 of the pawl 45 provides a cam surface engageable with the cam surface 39 of the cocking lever 36 to actuate the pawl in inward directions as aforesaid. Separate springs 48 and 49 are carried by the slider 35 and respectively engage the pawl 45 and the cocking lever 36 to load the two elements in firing pin-disengaging directions. That is to say, the spring 48 loads the pawl 45 for outward movement, while the spring 49 loads the cocking lever 36 for forward movement. Obviously, in view of the cam surfaces which interengage on the two parts, if the spring 48 is sufficiently strong, the spring 49 may be eliminated.

The operation of the cocking of the piece is readily understood from Figures 2 and 3. In Figure 2, the parts are shown in their normal positions with the cocking lever 35 forward and the pawl 45 moved outwardly to bring the rear surface of the arm 44 thereof into engagement with the cam surface 39 of the cocking lever, Figure 2. In the position shown, the firing pin is retracted to a cocked position and a bullet-simulating slug is positioned forwardly thereof by means to be described later. With the parts positioned as in Figure 2, it is obvious that if the trigger is pulled and the firing pin projected forwardly, the barrel is clear and the bullet-simulating slug passes freely out of the same in a well known manner. After firing, the firing pin 18 is in the position shown in Figure 3, which is in the region of the forward end of the slot 32 in the barrel. To cock the piece, the gunner grasps the handle 38 of the cocking lever 36 and pulls the same rearwardly. The initial effect of such a rearward pull is to rock the lever rearwardly until the pin 41 engages in the notch 40 of such lever. Meanwhile, the interengaging cam surfaces of the lever and pawl have caused the pawl to be moved inwardly to project the arm 46 thereof into the barrel through the slot 32 forwardly of the head 19 of the firing pin. Thereafter, continued rearward pulling movement on the handle 38 causes the slider 35 to move rearwardly taking with it the pawl 45 and the firing pin 18 against the action of the spring 16. This action is continued until the sear 26 engages in front of the plunger head 19. The grip on the handle 38 is now released and the

spring 48 and/or the spring 49 return the cocking lever and the pawl to their Figure 2 positions clear of the barrel. Thereafter, the slider is manually slid forwardly to the forward end of the slide to position the same for the next reloading operation.

The magazine 50 for the piece is best seen in Figures 4 and 5, as well as Figure 1, and comprises a tubular casing, the sides of which are formed with longitudinally-extending vertically-disposed slots 51. A spring 52 is interposed between the floor 53 of the magazine and a follower 54. The spring 52 is effective to load the follower 54 for movement upwardly of the magazine from the floor 53 thereof. The magazine 50 is of rectangular tubular shape, whereby to provide a close fit with a plurality of bullet-simulating slugs 55 which are adapted to be slidably received in the magazine atop the follower 54. The upper end of the magazine 50 is open, as at 56, to permit free passage of the slugs 55 upwardly and outwardly of the magazine. The upper end of the magazine 50 is slidably received in a vertically-directed aperture 57 formed through the stock 10. Such aperture 57 is vertically aligned with the complementary aperture 58 formed in the under surface of the barrel 13, whereby slugs 55 are fed to the barrel upon retraction of the firing pin 18, but are prevented from entering the barrel when the firing pin is projected, as shown in Figure 4, by virtue of the extension of the spring 16 across the opening 58. The front and rear sides of the magazine 50 are formed with a pair of rearwardly and forwardly-directed lugs 59 and 60, respectively, which are adapted to engage spring latches 61 and 62 carried by the under surface of the stock 10 in the region of the aperture 57. Such lugs 59 and 60 and latches 61 and 62 serve to detachably retain the magazine 50 in operative position relative to the piece. The follower 54 has fixed therein a pin 63, the opposite ends of which extend laterally outwardly of the same and of the magazine 50 through the slots 51 to provide finger grips, whereby the follower is readily retracted to permit reloading of the magazine when the same is empty.

As will be apparent from the foregoing, when the firing pin 18 is retracted and engaged by the sear 26, the same is positioned rearwardly of the aperture 58 in the under surface of the barrel. With the parts in this position, and the magazine 50 attached to the gun, the spring 52 and follower 54 feed the uppermost slug 55 into the barrel through the aperture 58 which is now unobstructed by either the firing pin or the spring 16. Upon pulling of the trigger lever 23, the firing pin moves forward rapidly and fires the slug in front of the pin outwardly of the barrel in a well known manner. At the same time, the firing pin spring 16 is extended across the opening 58 in the barrel, whereby to prevent the entrance of a slug 55. The cocking action previously described is now enacted, whereupon a succeeding slug 55 is fed to the barrel and the piece is ready to fire.

It is thus apparent that I have devised a repeating toy rifle which closely simulates the bolt action of an army rifle, and which automatically feeds a slug into the firing chamber of the piece upon each actuation of the bolt handle simulating cocking lever 36 and the related parts. While I have shown and described what is now thought to be a preferred embodiment of the invention, it is to be understood that the same is susceptible

of other forms and expressions. Consequently, I do not limit myself to the precise structure shown and described hereinabove except as hereinafter claimed.

I claim:

1. In a toy rifle including a stock, a barrel fixed to said stock, a spring-loaded firing pin in said barrel, and trigger-actuated sear means automatically locking said pin in a cocked position upon retraction of said pin, the improvement comprising a cocking lever simulating a bolt handle, means pivotally and slidably mounting said lever on said stock for sliding movement longitudinally of said barrel and forward and rearward pivotal movement on an axis transverse to that of said barrel, said barrel being formed with a longitudinal slot therein adjacent said lever, a cocking pawl pivoted to said means for inward and outward pivotal movement into and out of said barrel through said slot, interengaging cam surfaces on said lever and pawl whereby successive rearward rocking and sliding of said lever is operative to move said pawl into said barrel forwardly of said pin and thereafter move said pawl and pin rearwardly to cock the latter, and a spring means loading said pawl and lever respectively for outward and forward movement so as to locate said pawl normally outwardly of said barrel.

2. In a toy rifle including a stock, a barrel fixed to said stock, a spring-loaded firing pin in said barrel, and trigger-actuated sear means automatically locking said pin in a cocked position upon retraction of said pin, the improvement comprising said barrel being formed with a longitudinally-extending slot therein, at least one slideway formed on said stock in spaced parallel relation to said slot, a slider slidably mounted on said slideway, a cocking lever pivoted on said slider for forward and rearward pivotal movement, a cocking pawl pivoted on said slider for inward and outward pivotal movement, interengaging cam surfaces on said lever and pawl whereby successive rearward movement of said lever and rearward sliding of said slider moves said pawl inwardly into said barrel forwardly of said pin and thereafter moves said pawl and pin rearwardly to cock the latter, and a spring means

loading said pawl and lever respectively for outward and forward movement so as to locate said pawl normally outwardly of said barrel.

3. In a toy rifle including a stock, a barrel fixed to said stock, a spring-loaded firing pin in said barrel, and trigger-actuated sear means automatically locking said pin in a cocked position upon retraction of said pin, the improvement comprising said barrel being formed with a longitudinally-extending slot therein, at least one slideway formed on said stock in spaced parallel relation to said slot, a slider slidably mounted on said slideway, a bolt handle, means mounting said handle on said slider for movement forwardly and rearwardly relative thereto, a cocking pawl, means movably mounting said pawl on said slider for inward and outward movement into and out of said barrel through said slot, interengaging cam surfaces on said bolt handle and pawl whereby successive rearward movement of said lever and rearward sliding of said slider moves said pawl through said slot inwardly into said barrel forwardly of said pin and thereafter moves said pawl and pin rearwardly to cock the latter, and a spring means loading said pawl and bolt handle respectively for outward and forward movement so as to locate said pawl normally outwardly of said barrel.

ROY NASELLO.
